ATTORNEY.

UNITED STATES PATENT OFFICE.

ROBERT P. RANKIN, OF CLAYTON, INDIANA.

AUTOMATIC GUARD FOR ELEVATORS.

SPECIFICATION forming part of Letters Patent No. 267,757, dated November 21, 1882.

Application filed March 14, 1882. (No model.)

To all whom it may concern:

Be it known that I, ROBERT P. RANKIN, of the town of Clayton, county of Hendricks, and State of Indiana, have invented certain new and useful Improvements in Automatic Guards for Elevators, of which the following is a specification.

The object of my said invention is to produce a guard-rail for elevators which shall be automatically operated by the elevator itself as it passes up and down. This object is accomplished by forming in the sides of the elevator-platform curved slots which will engage with and operate projecting pins or arms on the inside of the hatchway, these pins being attached to and operating rising and falling arms, which in turn operate the vertically-movable guard-rails, and suitable catching and disengaging devices whereby the parts are held in position or disengaged therefrom, as will be hereinafter more particularly described and claimed.

Referring to the accompanying drawings, which are made a part hereof, and on which similar letters of reference indicate similar parts, Figure 1 is a perspective view of so much of an elevator and its surroundings as is necessary to illustrate my said invention; Fig. 2, a plan of the open hatchway and surrounding guard-rails; Fig. 3, a vertical section through the center of the hatchway and elevator; Fig. 4, a view similar to Fig. 3, except that the elevator-platform is level with the top of the floor surrounding the hatchway and the guard-rails depressed; Fig. 5, a horizontal section of one and a part of two other sides of the hatchway on the dotted line $z z$, Fig. 6; Fig. 6, a side elevation of one of the guard-rails and connected mechanism as seen from inside of the hatchway, the piece of timber forming the hatchway-lining being removed; and Fig. 7, an under side plan of the parts shown in Fig. 6, except that the hatchway-lining is replaced.

In said drawings, the portions marked A represent the frame-work surrounding the hatchway; B, the guard-rails; C, the arms which operate the guard-rails; D, the arms which operate the arms C; E, projecting lugs or cross-bars on the lower ends of the arms D; F, springs which catch and hold said cross-bars in position; G, push-pins by which the en-

gagement of said springs is released, and H the elevator-platform.

The frame-work A is similar to any ordinary frame-work surrounding the hatchway of an elevator, except that just outside its inner face is a narrow slot, in which the guard-rails and the arms which operate them are situated.

The guard-rails B are preferably rods of iron or gas-pipe extending across the width of the hatchway and turned down at each end at right angles with its main portion, said ends extending down through the floor or frame-work, in which are eyes or other suitable bearings for their reception.

The arms C are pivoted to the frame-work at their lower ends by the pivots c, and are provided at their upper ends with eyes c', which surround the main portion of the guard-rails. When these arms are forced up by the action of the other mechanism they carry the guard-rails with them.

The arms D are pivoted to the arms C by the pivots d, and are provided at their lower ends with cross-bars E, which rest in slots a in the frame-work. As said cross-bars are forced back and forth by the action of the passing elevator the other ends of these arms, and with them the arms C and the guard-rails, are forced up and down.

The springs F are preferably flat springs, secured to the frame-work at one end and provided with a hook or catch upon the other, adapted to catch over the end of the cross-bars E and hold the arms D forward, and thus hold the arms C and guard-rails B in elevated position when said cross-bars are forced to a position where such engagement can be made.

The push-pins G move laterally in proper bearings in the frame-work, and are adapted, when pushed upon by the passing elevator-platform or other means, to push upon the springs F and force them back until the catches thereon become disengaged from the cross-bars E, thus enabling said cross-bars to recede and permit the arms and guard-rails to drop into their recesses in the floor or frame-work.

The platform H has in its sides curved or cam-like grooves h, which, as said platform passes through the hatchway, engage with the cross-bars E and force them back and forth, with the result hereinbefore specified. It also

comes in contact with the push-pins G, forcing them and the springs F back, so that the catches on the latter will be disengaged from the cross-bars E and the latter left free to be moved back and forth in the slots a.

The operation of my said invention may be recapitulated as follows: The elevator-platform, in passing through the hatchway, first strikes the push-pin, G, forcing them and the springs F back until the cross-bars E are disengaged. The slots h then commence to operate upon said cross-bars, and through the arms D and C upon the guard-rails, gradually lowering the latter until, when the ends of the cross-bars have reached the center of the slots h and the top of the elevator-platform is level with the floor, said guard-rails are also level with the floor. When the elevator is again put in motion the slots h operate to force the cross-bars E and the arms D and C in the reverse direction to that just described, forcing up the guard-rails to the position shown in Figs. 1 and 3, and just as it leaves the hatchway releases its pressure upon the push-pins G, enabling the springs F to spring forward and the catches on the ends of the same to catch and hold the cross-rods E, thus securing all the parts against retrogression until again forced down by another passage of the elevator.

Having thus fully described my said invention, what I claim as new, and desire to secure by Letters Patent, is—

1. The combination of the hatchway, a recess in the floor or frame-work surrounding the same, a guard-rail, B, consisting of a horizontal and two vertical bars, as shown, said vertical bars passing through and adapted to move vertically in eyes or similar bearings in or near the ends of said recesses, below the floor-surface, all substantially as shown and specified.

2. The combination of the guard-rail B, arms C and D, cross-bar E, and platform H, having curved slots h, substantially as described, and for the purposes specified.

3. The combination, with guard-rail mechanism for an elevator, of springs F, push-pins G, and the elevator-platform, adapted to operate said push-pins and force a disengagement between catches on said springs and said guard-rail mechanism, substantially as set forth.

In witness whereof I have hereunto set my hand and seal, at Indianapolis, Indiana, this 10th day of March, A. D. 1882.

ROBERT P. RANKIN. [L. S.]
In presence of—

C. BRADFORD,
CHAS. L. THURBER.
